UNITED STATES PATENT OFFICE.

ISIDOR J. KUSEL, OF CHICAGO, ILLINOIS, ASSIGNOR TO STRONGHART COMPANY, OF CHICAGO, ILLINOIS, A CORPORATION OF ILLINOIS.

SAVINGS BANK.

Application filed July 23, 1921. Serial No. 436,928.

To all whom it may concern:

Be it known that I, ISIDOR J. KUSEL, a citizen of the United States, residing at Chicago, in the county of Cook and State of Illinois, have invented a certain new and useful Improvement in Savings Banks, of which the following is a full, clear, concise, and exact description, reference being had to the accompanying drawings, forming a part of this specification.

My invention relates to savings banks, particularly small metallic banks adapted to receive and hold a collection of coins and to be opened only by some authorized person, such as the cashier of a banking institution, where the owner of the small bank has a savings account.

One of the objects of the present invention is to provide a simple, practical and desirable construction of a small savings bank of the class specified.

Another object of the invention is to provide for the simple and ready opening of the bank by an authorized person, without any likelihood of the bank being opened by unauthorized persons.

Another object of the invention is to provide simple and effective means for preventing the removal of the coins by unauthorized persons.

In the accompanying drawings—

Fig. 1 is a side elevation, with a portion broken away, of a bank embodying my present invention;

Fig. 2 is a cross-section taken on line 2—2 in Fig. 1;

Fig. 3 is a horizontal section taken on line 3—3 of Fig. 1;

Fig. 4 is a view of a detail of construction;

Fig. 5 is a view of another detail of construction;

Fig. 6 is a view of the bottom of the bank completely detached from the body thereof; and

Figs. 7 and 8 are views of details of construction of a modified form.

Referring to the drawings, I show in Figs. 1 to 5, inclusive, a small savings bank consisting of a shell or casing 1, having a supporting and carrying handle 2. The shell or casing 1 is preferably of an oval cross-section as shown in Fig. 8, with the

top closed and the bottom open. A bottom 4 is fitted into the open lower end. A slot 5 is provided for the insertion of coins.

To prevent coins falling out of the slot 5 or being improperly extracted therefrom, rollers 6—6 are mounted inside of the casing 1 and opposite the slot 5. Coins may be passed through the slot 5 and between the rollers 6—6 to insert them into the bank, but may not be extracted therefrom because they will not pass of their own volition between the rollers 6—6. Furthermore, rollers 6—6 are well inside of the bank, removed from slot 5 so that access to said rollers through the slot 5 to tamper with same will be difficult if not impossible.

The bottom 4 fits removably into the open end of the shell or casing 1 and is detachably held therein by means of fastenings at its opposite end. Such fastenings comprise clips 8 and 9 at the opposite ends of the bank, the clip 8 being provided with a curved projection 10 and the clip 9 with a similar projection 11, the projections 10 and 11 forming abutments or engaging members. These engage the member 10 by a shank 12 on said bottom 4 and the member 11 by the tongue 13 of a lock 14 secured to said bottom 4. The tongue or bolt 13 may be operated by a key adapted for insertion in an aperture 15 in the bottom 4. Thus, the member 4 may be put in position by causing the clip 12 to engage abutment 10 and then pushing the other end of the bottom into position and causing or permitting the bolt 13 to engage abutment 11. To unlock the bank, and take the coins out the bolt 13 will be thrown by the key and then the bottom 4 removed and the coins taken out. The key for lock 14 is preferably in the hands of some officer of the banking institution who will open the bank when presented to him and take the coins and deposit them in the savings account.

In the bank shown in Figs. 1 to 6, inclusive, the clips or brackets 8 and 9 are in curved form, as shown in Fig. 5, being preferably riveted into place by rivets 16—16. In the modifications shown in Figs. 7 and 8, the continuous rims or abutments provided by the flanges 10 and 11 on clips 8 and 9 are replaced by lugs 17—17 formed at the ends of a clip or bracket 18, which is also riveted

in place. These lugs 17-17 act as stops to limit the inner movement of the bottom and the abutments for engagement by the prong and locking bolt of the bank bottom 5 are provided by projections 19, which are formed by punched portions of the clip or bracket 18, as shown in Fig. 7.

It will be seen that the bottom 4 is completely removable, permitting quick and 10 ready extraction of the coins. Also that said bottom may be easily and quickly attached and detached, being in effect hooked at one end and locked at the other. Also that the bottom is seated or held against 15 inward movement and may be readily jammed and clasped in place by simply pushing it into position in the bottom of the bank.

It will be understood that changes and 20 modifications may be made without departing from the spirit of the invention.

What I claim is:

1. A small bank comprising a shell or casing made in oval form and having its lower end open, a removable bottom fitted 25 to said open end, abutments on the inner side of the shell or casing near the open end, a prong to engage one of said abutments, and a lock to engage the other.

2. A small bank comprising a shell or 30 casing made in oval form and having its lower end open, a removable bottom fitted to said open end, abutments on the inner side of the shell or casing near the open end, a prong to engage one of said abutments, and a lock to engage the other, said abutments being also adapted to serve as stops to limit the inward movement of said bottom.

In witness whereof, I hereunto subscribe 40
my name this 17th day of June, A. D., 1921.

ISIDOR J. KUSEL.
